US0D1026765S

(12) **United States Design Patent** (10) **Patent No.:** **US D1,026,765 S**
(45) **Date of Patent:** **** May 14, 2024**

(54) **INSTRUMENT PANEL FOR A MOTOR VEHICLE**

(71) Applicant: **TOYOTA JIDOSHA KABUSHIKI KAISHA**, Toyota (JP)

(72) Inventor: **Hisato Sawada**, Nisshin (JP)

(73) Assignee: **TOYOTA JIDOSHA KABUSHIKI KAISHA**, Toyota (JP)

(**) Term: **15 Years**

(21) Appl. No.: **29/849,310**

(22) Filed: **Aug. 10, 2022**

(30) **Foreign Application Priority Data**

Feb. 15, 2022 (JP) ..... 2022-002764 D

(51) **LOC (14) Cl.** **12-16**

(52) **U.S. Cl.**

USPC **D12/192**

(58) **Field of Classification Search**

USPC D10/98; D12/114, 190-192, 415;
D23/324

CPC B60Q 3/10; B60D 25/14; B60K 35/00;
B60R 21/045
